[57] CLAIM

The ornamental design for a cremation urn, as shown and described.

DESCRIPTION

FIG. 1 is a top plan view of a cremation urn showing my new design;

FIG. 2 is a front elevational view of the cremation urn;

FIG. 3 is a right side elevational view of the cremation urn; and

FIG. 4 is a bottom plan view of the cremation urn. The left side is identical to the right side, and the rear is identical to the front. The top, sides, front and rear are all of a marble surface as partially shown in FIG. 3.
